UNITED STATES PATENT OFFICE.

ALEXANDER McDOWELL, OF LYNN, MASSACHUSETTS; IDA R. McDOWELL, ADMINISTRATRIX OF ALEXANDER McDOWELL, DECEASED, ASSIGNOR TO VALENTINE H. McDOWELL, OF LYNN, MASSACHUSETTS.

POLISHING-ROLL.

1,216,244.

Specification of Letters Patent. Patented Feb. 13, 1917.

Application filed April 3, 1913. Serial No. 758,725.

To all whom it may concern:

Be it known that I, ALEXANDER McDowell, a citizen of the United States, and resident of Lynn, in the county of Essex and 5 State of Massachusetts, have invented certain new and useful Improvements in Polishing-Rolls, of which the following is a specification.

This invention relates to an improved 10 roll adapted for use in the arts for the purpose of giving a polished finish to articles of all sorts. The purpose of the invention is to provide a new construction of roll whereby the same may be maintained in 15 sufficiently firm condition to do its work properly, without at the same time being made too hard, and in which also the degree of capacity of yielding of the operating surface may be regulated and adjusted without 20 causing a departure from the true circular form. The precise nature of the roll which I have devised to have these characteristics is set forth in the following specification, and illustrated in the drawings accompany- 25 ing the same. These drawings show the preferred embodiment of my invention in practical form, without being intended to represent the only possible embodiment or to limit the invention beyond the statement 30 in the broadest of the appended claims.

In the accompanying drawings,

Figure 1 is a perspective view of the roll.

Fig. 2 is a longitudinal section of the same through the axis.

Fig. 3 is a cross section of the roll and

Fig. 4 is an elevation showing the body or core of the roll with the surface layer or facing removed.

Fig. 5 represents a view similar to a portion of Fig. 2 the outer covering being omitted.

The same reference characters indicate the same parts in all the figures.

The roll embodies in its construction a 45 body portion *a* and a surface element or layer *b* surrounding the body portion and forming the operating face which acts directly on the article to be polished. The body is made preferably of rubber, as that 50 substance has the desired qualities of perfect elasticity, resilience, and softness or capacity for distortion to a great extent,

within the elastic limit. By specifying rubber at this point I do not intend to limit my invention to the use of that particular 55 material for the body, but include within this element of the invention any other material having the above-mentioned qualities in either greater or less degree than rubber.

This elastic body is mounted on a rigid 60 sleeve or tube *c* which forms the hub of the roll and is adapted to be secured firmly to any rotatable shaft *d*, in any manner, whether as shown in Fig. 2 or otherwise. Mounted upon the sleeve or tubular hub *c* 65 are disks or heads *e*, *f* which are located adjacent to the opposite end faces of the elastic body and which are confined between abutments *g*, *h* on the sleeve, one of which abutments, as *h*, is adjustable and may be 70 a nut threaded upon the sleeve. These disks or heads are preferably made convex on the sides toward the elastic body so that when forced together they will compress the axial portion of the body and expand its peripheral portion radially upward. Between the disks and the body are washers *i*, adapted to 75 conform to the convex faces of the respective heads and made of a material which will slide easily on the material of the heads. 80 Without intending to limit myself to the use of any specific materials I will state that in practice I have found it suitable to make the heads of brass and the washers of steel. The washers are provided to guard 85 against any twisting and possible tearing of the elastic body due to the turning of either or both heads which may result when they are forced together by such a rotatable adjuster as the nut *h*. Where the adjustment may be produced without tendency to rotate either head, the washers may be dispensed with.

The surface covering *b* of the roll may be 95 of any nature suitable for the work which the roll is designed to perform. It may be of soft and yielding material such as felt, or it may be a sheet coated with abrasive material. When it is of soft material it is attached to a comparatively firm and inelastic, but flexible fabric such as cotton duck, a layer of which is indicated in the drawings at *k*. The sheet or strip of such fabric which thus forms the lining and carrier 100

for the surface layer has its ends joined by a seam at *l* to make a band, and the edges at the seam are turned inward and occupy a groove in the surface of the elastic body. 5 The band carrying the surface layer may be slipped endwise on and off the body when the latter is relaxed in consequence of loosening of the binding heads, and when placed on the elastic body is clamped by radial outward pressure of such body produced by 10 tightening up the heads. The friction between the surface of the body and the lining *k*, together with the positive lock formed by the inturned edges of the seam in the 15 groove of the body, prevents the surface layer from slipping about the body when the latter is rotated.

In the peripheral face of the body are a series of cuts or gashes *m* which extend 20 diagonally or spirally with relation to the axis of the roll, as indicated in Fig. 4, and extend inward a short distance from the periphery of the body as indicated in Figs. 1 and 3. These cuts destroy the continuity of 25 the peripheral portion of the elastic body and thereby perform an important function as hereinafter explained.

It will be understood from the foregoing description that axial pressure of the 30 adjusting heads upon the elastic body will cause the same to expand toward the covering. Distortion of the body is thereby occasioned throughout so much of it as remains homogeneous, but the surface layer 35 which is intersected by the cuts *m* is not homogeneous with the rest of the body but is discontinuous. Hence the discontinuous segments between the cuts are left in their natural state when the central part of the 40 body is distorted and are caused to transmit only radial pressure, which is uniform at all points angularly about the axis. The discontinuity of the peripheral portion prevents any tendency of any part of the body 45 to exert greater pressure than any other part on the covering of the roll and thereby to distort the covering from true circular form. Hence the roll is kept true under all conditions of pressure. The elastic body 50 may be placed under any desired degree of tension so as to take up all slack in the covering and expand the latter smoothly and give it any desired degree of firmness or softness. At the same time, however great 55 the pressure thus exerted outwardly may be, the covering is never made hard but is able to yield. This is especially valuable where the covering is of felt, which, if placed on an unyielding body or form would quickly 60 become hard packed, but which, when placed on a rubber body of the character described, does not become packed hard although it is sufficiently firm to apply the necessary amount of pressure to polish the article 65 acted upon.

I am aware that other gums and compositions than rubber are soft, yielding, and highly elastic. Consequently, I reserve the right to use any of such compositions to make the elastic body.

The covering layer *k* may be used without the surface covering *b* as shown by Fig. 5 and may be composed of textile fabric having a frictional surface such as twilled or coarsely woven duck or canvas or corduroy, 70 the covering layer being thus adapted to polish surfaces of heels and soles and other articles.

I claim:

1. A polishing roll comprising an elastic 80 body having a discontinuous peripheral portion, a separate covering surrounding such peripheral portion and means for compressing the central part of said body axially whereby to produce a radial outward pressure upon the covering.

2. A polishing roll comprising a rigid hub, an elastic yielding body surrounding said hub of continuous structure at its inner part and discontinuous at its exterior, a covering of material suitable for polishing surrounding said body and compression heads mounted on the hub on each side of the body movable axially toward and from one another, whereby to produce radial pressure of 95 the body against the covering.

3. A polishing roll comprising a body portion of rubber or substantially equivalent yielding and elastic material formed with its peripheral part interrupted and discontinuous, a hub contained centrally in said body portion, heads mounted on said hub at opposite ends of the body portion, means for forcing one of said heads toward the other against the body portion, whereby to distort and force the peripheral portion thereof outwardly, and a covering band surrounding and filled by the body portion.

4. A polishing roll comprising a hub, a generally cylindrical body portion of rubber, on said hub, a covering consisting of a layer of felt and a lining band of inextensible fabric surrounding the elastic body, said band having a seam with inturned edges interlocked with the body, and compression heads mounted on the hub at opposite ends of the roll adapted to be forced together to compress the elastic body axially and thereby expand its peripheral portion radially, such peripheral portion being discontinuous, whereby the expansive pressure is evenly distributed.

5. A polishing roll comprising a generally cylindrical body of elastic material having inclined or diagonal cuts in its periphery, a hub in the axis of said body, heads mounted on said hub at opposite ends of the body, anti-friction washers between the heads and the body, a nut threaded upon the hub engaging one of said heads and operable to ad- 130

just the latter toward the other head, and a polishing covering layer surrounding the elastic body.

6. A polishing roll comprising a hub, a generally cylindrical body portion of rubber, on said hub, a covering consisting of a layer of felt and a lining band of inextensible fabric surrounding the elastic body, said band having a seam with inturned edges interlocked with the body, and compression heads mounted on the hub at opposite ends of the roll adapted to be forced together to compress the elastic body axially and thereby expand its peripheral portion radially.

7. A polishing roll comprising a hub, a generally cylindrical body portion of elastic material, on said hub, a covering consisting of a band of inextensible fabric surrounding the elastic body, said band having a seam with inturned edges interlocked with the body, and compression heads mounted on the hub at opposite ends of the roll adapted to

be forced together to compress the elastic body axially and thereby expand its peripheral portion radially, such peripheral portion being discontinuous, whereby the expansive pressure is evenly distributed. 25

8. A polishing roll comprising a hub, a generally cylindrical body portion of elastic material, on said hub, a covering consisting 30 of a band of inextensible fabric surrounding the elastic body, said band having a seam with inturned edges interlocked with the body, and compression heads mounted on the hub at opposite ends of the roll adapted to 35 be forced together to compress the elastic body axially and thereby expand its peripheral portion radially.

In testimony whereof I have affixed my signature, in presence of two witnesses.

ALEXANDER McDOWELL.
